UNITED STATES PATENT OFFICE.

GUSTAV A. LUND, OF MILWAUKEE, WISCONSIN.

AEROPLANE.

Application filed September 29, 1927. Serial No. 222,884.

This invention relates to aeroplanes and more particularly to means for lifting the same in the air, and it consists in the novel features hereinafter described and claimed.

5 An object of the invention is to provide lifting means which utilize the resistance of the air which is encountered by the aeroplane, when moving in a forward direction by deflecting air currents inwardly toward 10 the body or fuselage of the machine and impinging said currents upon lifting planes mounted at the sides of the fuselage, whereby by the said air currents are caused to assist in the lifting of the plane.

15 With this object in view, the structure includes the provision of fans at the underside of the sustaining plane of the aeroplane, and in the vicinity of the ends thereof. These fans are provided with 20 means for drawing in currents of air and for deflecting the said currents of air inwardly toward the fuselage. Lifting planes are mounted at the opposite sides of the fuselage and said currents of air are impinged upon the surfaces of the lifting planes. Means are provided for varying the 25 angle of inclination of the lifting planes with relation to a horizontal line so that the aeroplane may be lifted at a desired 30 angle with relation to the surface of the ground.

In the accompanying drawings:

Figure 1 is a top plan view of the improved aeroplane, with parts thereof broken away, and parts shown in section;

Figure 2 is a vertical front elevational view thereof;

Figure 3 is an enlarged fragmentary sectional view of one of the fans and lifting planes of the aeroplane.

As illustrated in the accompanying drawings, the aeroplane includes a fuselage or body 1 of conventional form, having a sustaining plane 2 disposed transversely thereof in the usual manner. Brackets 3 are arranged at the opposite sides of the fuselage 1 and those brackets which are nearer the forward end of the fuselage 1 are longer than those disposed toward the rear end of the fuselage. The brackets 3 are substantially under the sustaining plane 2. Lifting planes 4 are pivoted between the brackets 3 and said planes are located one at each

side of the fuselage 1. Rods 5 are connected with the upper portions of the lifting planes 4 and enter the body of the fuselage as best shown in Figure 1 of the drawings, and may be used for tilting the planes 4 in the brackets whereby the angle of inclination of the said planes with relation to the axis of the fuselage and a horizontal line may be varied.

Fan casings 6 are carried at the under side of the sustaining plane 2 in the vicinity of the ends thereof, and fan blades 7 are mounted for revolution in said casing. The blades 7 are mounted upon shafts 8, which are journaled in the sides of the casings, and which are provided at their rear ends with bevelled pinions 9 which mesh with similar pinions 10, mounted upon a shaft 11 which is disposed transversely of the fuselage and which may be rotated by an engine (not shown) carried in the fuselage in any suitable manner. The casings 6 are provided at their forward sides with centrally located air intake openings 12 and the said casings are provided at their inner sides and at their edges with discharge outlets 13 which are directed toward the outer surfaces of the lifting planes 4 and spaced therefrom.

It will be seen that when the shaft 11 is rotated rotary movement is transmitted to the shafts 8 which in turn carry the blades 7 around in the casings 6, and the said blades draw currents of air into the casings through the inlet openings 12 and direct the said currents of air through the discharge outlets 13 toward the lifting planes 4. As the said currents of air impinge upon the outer surfaces of the planes 4, they have a tendency to lift the aeroplane vertically. By varying the angle of the lifting planes, the angle of elevation of the aeroplane may be varied. It is obvious that this lifting action may be caused to take place when the aeroplane is in flight or when it is being wheeled or moved over the surface of the field.

From the foregoing description of the construction of my improved device, it will be seen that I have provided a simple, inexpensive and efficient means for carrying out the objects of the invention and while I have particularly described the elements best adapted to perform the functions set forth,

it is obvious that various changes in form, proportion and in the minor details of construction may be resorted to without departing from the spirit or sacrificing any of the 5 principles of the invention.

Having described the invention, what is claimed is:

1. An aeroplane comprising a fuselage, a sustaining plane mounted thereon, lifting 10 planes carried at the sides of the fuselage and disposed below the sustaining plane, fan casings carried at the under side of the sustaining plane and located at opposite sides of the fuselage, said fan casings having 15 inlet openings disposed toward the forward edge of the sustaining plane and discharge outlets disposed inwardly toward the lifting planes, fan blades mounted for rotation in the casings and means for rotating the 20 blades.
2. An aeroplane comprising a fuselage having a sustaining plane disposed transversely over the top thereof, lifting planes carried by the fuselage below the sustaining 25 plane and disposed at opposite sides of the fuselage and fans carried by the sustaining

plane and disposed at opposite sides of the fuselage, and adapted to impinge currents of air upon the lifting planes.

3. An aeroplane comprising a fuselage, a 30 sustaining plane mounted thereon, lifting planes carried by the fuselage and arranged below the sustaining plane at opposite sides of the fuselage, means for varying the angle of inclination of the lifting planes and fans 35 carried by the sustaining plane and disposed at opposite sides of the fuselage and arranged to discharge currents of air inwardly upon the lifting planes.

4. An aeroplane comprising a fuselage, a 40 sustaining plane mounted thereon, lifting planes carried by the fuselage at the opposite sides thereof and disposed at an angle with relation to the axis thereof, means for varying the angle of inclination of the lifting 45 planes and fans carried under the end portions of the sustaining plane and disposed at opposite sides of the fuselage and adapted to direct currents of air inwardly upon the lifting planes.

In testimony whereof I affix my signature.
GUSTAV A. LUND.
